3,269,379 FLUID POWERED GUN

Guy E. Braughler and Ronald W. Joyce, Rogers, Ark.,
assignors to Daisy Manufacturing Company, Rogers,
Ark., a corporation of Nevada
Filed June 30, 1964, Ser. No. 379,213
3 Claims. (Cl. 124—11)

This invention relates generally to fluid powered guns adapted to propel BB's or other projectiles and more particularly to an improved feed mechanism for a fluid powered gun.

Fluid powered guns heretofore known and used generally utilize relatively complex propulsion mechanisms having a limited projectile capacity. Such known guns also are relatively difficult to load and the projectiles difficult to position for semi-automatic discharge.

Accordingly, one object of the present invention is a fluid powered gun having a relatively simple propulsion mechanism for propelling BB's, pellets or slugs each time the trigger of the gun is pulled.

Another object of the invention is a fluid powered gun having a projectile elevator which is automatically charged after each projectile is propelled from the barrel of the gun.

Another object of the invention is an improved feed mechanism for a fluid operated gun.

Further objects and advantages of the invention may be apparent from the following specification, appended claims and accompanying drawings in which:

FIGURE 1 is a side elevational view of an automatic fluid operated gun according to the present invention;

FIGURE 2 is a side elevational view similar to FIG. 1, showing the gun having a portion thereof broken away and in section;

FIGURE 3 is a side elevational view of the fluid powered gun with the barrel housing removed, and

FIGURE 4 is a view of the back side of the gun of FIG. 3.

As shown in FIGURES 1 and 2 of the drawings a fluid-operated gun 10, in accordance with an exemplary constructed embodiment of the instant invention, is of pistol configuration including a barrel 12, trigger 14, handle 16 and barrel housing 18. The handle 16 encloses a conventional gas container 20.

As seen in FIGURE 2 of the drawings, the barrel 12 is supported by a frame member 32. The frame member 32 has a bore 34 in which a tubular valve plunger 36 is slidably mounted. The plunger 36 has an open end portion 38 communicating with a central gas delivery passage 40.

The bore 34, within which the plunger 36 is slidably and reciprocally supported, intersects a bore 42 wherein a projectile elevator 44 is reciprocally supported. A spring 46 normally biases the elevator 44 downwardly against a stop pin 48 whereas the trigger 14 is operable to force the elevator 44 upwardly away from the pin 48 against the bias of the spring 46.

The trigger 14 is pivotally mounted on a pin 50 carried by the frame 32. The trigger has a pawl 52 engageable with a ledge 54 on the elevator 44 so that when the trigger 14 is pulled counterclockwise, as seen in FIG. 2, the elevator 44 is forced upwardly away from the pin 48. Upon upward movement of the elevator 44, an inclined portion 56 thereof passes the end portion 38 of the plunger 36 whereupon forward pressure of the plunger 36 caused by gas pressure acting thereon, as will be described, causes the end 38 to exert a vertical component of force on the elevator 44 sufficient to carry the elevator 44 upwardly against compression of the spring 46.

As soon as the elevator 44 has moved upwardly into

2

a position wherein a BB holding recess 60 therein is aligned with a central bore 62 in the barrel 12, fluid pressure is conducted through a passageway 64 and the central bore 40 in the plunger 36 from a chamber 66 surrounding the plunger 36 whereby a BB is propelled outwardly through the bore 62 of the barrel 12. Fluid under pressure is conducted to the chamber 66 from the container 18, through hollow needle 68.

The central passage 40 of the plunger 36 is normally isolated from the chamber 66 by a valve 70 carried by a reciprocable valve shaft 72. The valve shaft 72 is supported in a bore 74 in a packing nut 76 which is threadably secured to the frame 32.

Fluid pressure in the chamber 66 acts on the valve 70 tending to force it against an end portion 78 of the plunger 36, closing the bore 40 therein and forcing the plunger 36 to the left, as seen in FIG. 2, against the elevator 44. When the elevator 44 moves upwardly sufficiently that the end 38 on the plunger 36 contacts the inclined surface 56 on the elevator 44, the valve 70 and plunger 36 travel forwardly until a flange 80 on the shaft 72 contacts the nut 74 thereby abruptly stopping forward motion of the valve shaft 72 and 70. Forward inertia of the plunger 36 causes it to continue toward the elevator 44 thereby separating the hollow cylindrical end 78 thereof from the valve 70 and permitting fluid pressure in the chamber 66 to act on the rear end of the plunger 36. Thus plunger 36 continues to be projected forwardly towards the opening 64 in the elevator 44, gas being comitantly exhausted through the central bore 40 of the plunger 36. The gas passes directly into the recess 60 in the elevator 44 to force the BB therein outwardly of the bore 62 in the barrel 12. When fluid pressure in the chamber 138 is exhausted, a spring 82 forces the plunger 36 rearwardly causing the open cylindrical end 78 thereof to reengage the valve 70. Continued flow of fluid through the needle 68 builds up pressure in the chamber 66 while the spring 46 concurrently forces the elevator 44 downwardly into the position shown in FIG. 2 of the drawings.

As best seen in FIGURES 3 and 4 of the drawings, the fluid powered gun 10 is provided with a feed mechanism comprising an inlet aperture 100 in a rear end portion 102 of the frame 32. The aperture 100 is normally closed by a cover plate 104.

The aperture 100 communicates with a channel 106 in the frame 32, BB's being guided to the channel 106 by a guide plate 108. The BB's move up the channel 106 onto a ledge 110 on a forward portion of the frame 32. The BB's then pass over the barrel 12 and onto a ledge 112 on the opposite side of the barrel 12 from the ledge 110 (FIG. 4). The BB's then move forwardly on the ledge 112 then downwardly around the forward end thereof and rearwardly along an extension 114 of the handle 16. The BB's then move into a recess 116 in the frame 32 which leads into a rearwardly directed bore 118 which is aligned with the recess 60 in the elevator 44 when the elevator 44 is in its lowermost position as shown in FIGURE 2 of the drawings.

As best seen in FIGURES 2 and 3 of the drawings, a feed mechanism plunger 120 is slidably and retractably disposed in the bore 118 and is movable toward the elevator 44 under the bias of a spring 122. The plunger 120 biases the BB's in the bore 118 into the recess 60 in the elevator 44.

In order to charge the bore 118 with BB's the plunger 120 is movable away from the elevator 44 by a manual operator 124 against the bias of the spring 122 and the gun 10 pointed upwardly. BB's then roll downwardly into the bore 118 whereupon the plunger 120 is released. It is to be noted that upon firing of the last BB and end portion 126 of the plunger 120 enters the recess 60 in the

elevator 44 to preclude actuation thereof. Thus, the plunger 120 functions to indicate that the bore 113 is empty by preventing trigger actuation as well as to feed BB's to the elevator 44. Further, the aforementioned feed mechanism maximizes the BB capacity of the fluid powered gun as well as to insure positive feed of BB's to the propulsion mechanism. 5

While a preferred embodiment of the present invention has been illustrated and described in detail, various additions, substitutions, modifications and omissions may be 10 made thereto without departing from the spirit of the invention as incorporated by the appended claims.

What is claimed is:

1. A fluid powered gun comprising
a frame; 15
a barrel having a bore therethrough and supported on
one end of said frame;
a projectile elevator having a projectile holding recess
movable into alignment with said bore;
a source of fluid pressure; a fluid pressure control valve, 20
a normally closed hollow fluid pressure plunger, con-
duit means conducting fluid from said source for
biasing said plunger away from said valve to permit
the passage of fluid pressure into said plunger and
towards said elevator upon upward movement of 25
said projectile elevator,
a trigger for moving said projectile elevator upwardly
to a position in which the recess therein aligns with
the bore in said barrel and wherein said fluid pres- 30
sure plunger enters said recess to release fluid pres-
sure into said bore, spring means for normally biasing
said plunger towards said valve,
a projectile feed tube communicating with the projec-
tile receiving recess in said projectile elevator, 35
a feed plunger in said feed tube normally biased toward
the recess in said elevator for discharging projectiles
thereinto,
a projectile storage area located on the opposite side
of said feed tube from said projectile elevator, and 40
a projectile feed channel extending from the other end
of said frame and communicating with said projectile
storage area.
2. A fluid powered gun comprising
a frame; 45
a barrel having a bore therethrough and supported on
one end of said frame;
a projectile elevator having a projectile holding recess
movable into alignment with said bore;
a source of fluid pressure; a fluid pressure control valve, 50
a normally closed hollow fluid pressure plunger, con-
duit means conducting fluid from said source for
biasing said plunger away from said valve to permit
the passage of fluid pressure into said plunger and
towards said elevator upon upward movement of said 55
projectile elevator,
a trigger for moving said projectile elevator upwardly
to a position in which the recess therein aligns with
the bore in said barrel and wherein said fluid pressure
plunger enters said recess to release fluid pressure

into said bore, spring means for normally biasing
said plunger towards said valve,
a projectile feed tube communicating with the projectile
receiving recess in said projectile elevator,
a feed plunger in said feed tube normally biased to-
ward the recess in said elevator for discharging pro-
jectiles thereto,
a projectile storage area substantially surrounding said
barrel on the opposite end of said feed tube from
said projectile elevator, and
a projectile feed channel extending from the other end
of said frame to said projectile storage area.

3. A fluid powered gun comprising
a frame;
a barrel having a bore therethrough and supported on
one end of said frame;
a projectile elevator having a projectile holding recess
movable into alignment with said bore;
a source of fluid pressure; a fluid pressure control valve,
a normally closed hollow fluid pressure plunger, con-
duit means conducting fluid from said source for
biasing said plunger away from said valve to permit
the passage of fluid pressure into said plunger and
towards said elevator upon upward movement of said
projectile elevator,
a trigger for moving said projectile elevator upwardly
to a position in which the recess therein aligns with
the bore in said barrel and wherein said fluid pressure
plunger enters said recess to release fluid pressure
into said bore, spring means for normally biasing
said plunger towards said valve,
a projectile feed tube communicating with the projec-
tile receiving recess in said projectile elevator,
a feed plunger in said feed tube normally biased toward
the recess in said elevator for discharging projectiles
thereto,
a projectile storage area located on the opposite end of
said feed tube from said projectile elevator,
a projectile feed channel extending from the other end
of said frame and communicating with said projectile
storage area, said feed channel being disposed on
one side of said barrel and said feed tube communi-
cating with said storage area on the other side of said
barrel whereby the BB's move transversely of said
barrel within said storage area.
